SIGNAL DEVICE

Lloyd Rittenhouse, Honeoye Falls, N. Y., assignor
to The A. E. Rittenhouse Co., Inc., Honeoye
Falls, N. Y., a corporation of New York

Application October 12, 1938, Serial No. 234,643

3 Claims. (Cl. 116—149)

This invention relates to a signal device, with more particular reference to the type of apparatus employed as a door chime in dwellings, although equally adaptable to other purposes where an audible signal is to be given, and it has for its object to afford a simple, practical, and economical design that will afford pleasing tones, and is especially useful with a two-tone chime.

10 In a more specific aspect, the invention has to do with the type of construction in which a housing containing a resonance chamber, and a chime bar, are mounted on a supporting plate in parallel arrangement, together with striker 15 operating mechanism, and has for its purpose to afford a structure in which these parts are compactly and securely arranged, and a chime bar may be employed that is of considerably less length than heretofore used in such devices.

20 Another object of the invention is to afford a superior arrangement for mounting a chime bar and housing on a supporting plate, providing a rigid, compact, and economical construction that also gives a pleasing tone quality.

25 To these and other ends, the invention consists in the construction and arrangement of parts that will appear from the following description when read in conjunction with the accompanying drawings, the novel features being pointed 30 out in the claims following the specification.

In the drawing:

Fig. 1 is a front elevation of a signal device, incorporating one embodiment of the invention;

Fig. 2 is a vertical sectional view through the resonance chamber housings, with the top cover plate removed and showing the remaining parts in front elevation;

Fig. 3 is a side elevation of the parts appearing in Fig. 2, and

Fig. 4 is a similar view showing the relation between the chime bar and resonance chamber housing of the present invention.

The structure shown, which is intended only as illustrative of an exemplary embodiment of the invention, includes a removable top cover plate 1 that is detachably associated with a supporting plate 2 which is secured to any suitable wall or foundation, as usual in this class of apparatus.

The invention is illustrated as applied to a two-tone or two-chime signal, including chime bars 3 and 4 mounted edgewise on the supporting plate 2 and arranged to be operated by suitable electrically actuated striker mechanism

units 5 and 6 respectively, as usual in this type of signal.

Arranged for cooperation with the chime bars 3 and 4 are resonance chambers 7 and 8 formed in the housings 9 and 10, which are positioned in parallelism with the chime bars. The housings 9 and 10 are mounted on the supporting plate 2 by means of the attaching devices 11, with their upper ends in juxtaposition to the electric striker operating unit 5, this arrangement permitting the lower portions of the chime bars to be mounted on the housings.

The chime bars 3 and 4 have their upper portions mounted on brackets 12 and 13 which in turn are secured to the supporting plate 2, while the lower portions of the chime bars are attached to the upper ends of the housings 9 and 10 by means of suitable attaching devices 14 and 15, thus eliminating the necessity of additional brackets on the supporting plate for the lower portions of the chime bars.

Heretofore in structures of this character, the chime bar has extended beyond its lower point of attachment to the supporting plate a distance somewhat greater than the distance between its two points of attachment, enabling locating the opening in the resonance chamber midway between two nodal points of the chime bar.

In prior structures the chime bar has extended far enough beyond its point of attachment to provide a third nodal point, but in the present construction, the chime bars are shortened and the resonance chamber housings positioned higher, affording a more compact and economical design, without affecting the quality of tone of the chime bars.

This is illustrated in Fig. 5 where e and f indicate the two points of attachment of the chime bar to the supporting plate, or to the supporting plate and resonance chamber housing, the chime bar extending but a short distance below the nodal point f or lower point of attachment, while g represents the opening in the resonance chamber opposite the lower part of the chime bar immediately beneath the nodal point f and between it and the end of the bar, the upper end of the resonance chamber housing being located somewhat above the nodal point f.

Referring to Fig. 2, 16 designates the openings in the resonance chambers, opposite the lower portions of the chime bars 3 and 4 which extend slightly below the points of attachment 14 and 15 where they are mounted on the housings. With this arrangement, the chime bars extend below their lower points of attachment and above

their upper points of attachment similar short distances, while the upper ends of the resonance chamber housings are located above the lower points of attachment of the chime bars and in 5 juxtaposition to the striker operating mechanism. This arrangement permits the use of a chime bar of considerably less length than heretofore, and affords a more compact and economical way of locating and securing the chime bars and 10 housings on the supporting plate.

10 While the invention has been described with reference to the particular embodiment disclosed herein, it is not confined to this exact design, and the application is intended to cover such further modifications or departures as may come 15 within the purposes of the invention or the scope of the following claims.

I claim:

1. In a signal device, the combination with a 20 supporting plate, of a chime bar mounted thereon and having only two nodal points, the chime bar being attached at such nodal points and extending beyond said points of attachment less than half the distance between said points of attachment, and a housing mounted on the plate and embodying a resonance chamber, said hous- 25

ing being arranged parallel to the chime bar, and the resonance chamber having an opening located opposite the portion of the chime bar between one end and the nodal point nearest to that end.

2. In a signal device, the combination with a 5 supporting plate and a housing secured to the supporting plate and embodying a resonance chamber, of a chime bar attached to the plate and to said housing, the chime bar extending slightly beyond its points of attachment and the resonance chamber having an opening located opposite the portion of the chime bar between one end and the nodal point nearest to that end. 10

3. In a signal device, the combination with a supporting plate and striker mechanism secured 15 thereon, of a housing embodying a resonance chamber secured to the supporting plate with one end adjacent to said striker mechanism, and a chime bar attached to said supporting plate and to said housing at two points and extending beyond 20 said points of attachment less than half the distance between them, said resonance chamber having an opening located opposite the portion of the chime bar between one end and the nodal point nearest to that end. 25

LLOYD RITTENHOUSE.
